United States Patent Office.

GEORGE COOK, OF PARIS, ILLINOIS.

Letters Patent No. 70,805, dated November 12, 1867.

IMPROVEMENT IN ROOFING.

The Schedule referred to in these Letters Patent and making part of the same.

TO WHOM IT MAY CONCERN:

Be it known that I, GEORGE COOK, of Paris, Edgar county, Illinois, have invented a new and useful Improvement in Roofing; and I hereby declare the following to be a full, clear, and exact description thereof, reference being had to the accompanying drawings, making part of this specification.

This invention relates more especially to a peculiarly-formed tile for purposes of roofing or weather-siding, and to the method of attaching the same.

Figure 1 is a perspective view of a part of a roof embodying my invention.

Figure 2 is one of my tiles detached.

Figure 3 is the cap used for breaking the joints, and for clasping the tiles together.

A A are horizontal ribs or joists of a roof or wall. B B are tiles attached to the same by means of hasps C. The tile B (see fig. 2) has upturned edges D, and a raised part, E, the latter to allow of a groove, F, being formed beneath the tile to receive the upper end of the cap G, the said caps being used to break the joints between the tiles. The under side of the tile is shouldered at H, and its lower surface so raised from the said shoulder to its lower edge as to admit of the upper edge of the preceding course of tiles resting beneath it upon the rib A. The tiles are secured to the ribs or joists by means of hasps C, the said hasps having a cross-head, c, the ends of which lie in the gains d in the upper sides of the upturned edges D of the tiles. The lower end c of the hasps C is furnished with a screw or nail-hole, c', by which it is attached through the medium of screw or nail to the rib A. The upturned rib D is formed of gradually-increasing width towards the lower end. The cap G has a groove, g, beneath, of such form and size as to clasp the contiguous edges D D of two tiles. The similarly-inclined form and size of the groove g, and the ridge formed by the two edges D D enable the tightening of the joint between the tiles by driving the cap downward in the direction of its length. At the peak or comb of the roof the tiles are somewhat modified in form, those on one side being finished at top into the form of a half-round bead, I, and those on the other side having a groove, J, fitting the bead I, and curving so far around as to render the joint weather-tight.

In making a roof, the tiles of the lower course are laid on, and fastened in position one by one by the hasps C. The caps G are then put over the ridges D D, a little above the permanent position of the said caps, and where they can be put on with ease, and then driven down until sufficiently tight. In laying all subsequent courses the same method is followed, the shoulder H serving to hold the tile up in its proper place by resting upon the upper ends of the tiles of the course below, and by the upper end of the cap in the groove F.

It will be readily seen that this roof and siding has some great advantages over nearly all in common use, among which may be enumerated its easy application, extreme durability, and the protection afforded against fire, being in this latter respect superior to slate as a better non-conductor of heat, and not so liable to fly or crack.

I claim herein as new and of my invention—

1. A tile, B, of earthenware, stoneware, or other suitable material, having the parts D E F G H, substantially as shown and described.
2. In combination with the tile B, I claim the cap G, having a groove, g, as and for the purpose set forth.
3. In combination with the tile B, I claim the hasp C c c', as and for the purpose stated.
4. In combination with the elements D E F H, I claim the bead I, and grooved comb J for the different sides of the roof-peak, as and for the purpose set forth.

In testimony of which invention I hereunto set my hand.

GEORGE COOK.
